US0D1082778S

(12) **United States Design Patent** (10) **Patent No.:** **US D1,082,778 S**
(45) **Date of Patent:** **** Jul. 8, 2025**

(54) **COMPUTER HOST**

(71) Applicant: **Shenzhen Chuangyingxin Industrial Co., Ltd.**, Shenzhen (CN)

(72) Inventor: **Minghui Liu**, Shenzhen (CN)

(73) Assignee: **Shenzhen Chuangyingxin Industrial Co., Ltd.**, Shenzhen (CN)

(**) Term: **15 Years**

(21) Appl. No.: **29/921,702**

(22) Filed: **Dec. 19, 2023**

(51) LOC (15) Cl. **14-02**

(52) U.S. Cl.

USPC **D14/314**

(58) **Field of Classification Search**

(57) **CLAIM**

The ornamental design for a computer host as shown and described.

DESCRIPTION

FIG. 1 is a front, right and top perspective view of a computer host, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2; and, FIG. 11 is an enlarged view of detail 11 in FIG. 2.

The broken lines depict portions of the computer host that form no part of the claimed design.

The dot-dash broken lines depict the boundaries of the enlargements that form no part of the claimed design.

1 Claim, 11 Drawing Sheets
